UNITED STATES PATENT OFFICE.

GEORGES DELIN, OF BRUSSELS, BELGIUM.

INCANDESCENT GAS-LIGHTING BURNER.

SPECIFICATION forming part of Letters Patent No. 668,628, dated February 26, 1901.

Application filed July 14, 1900. Serial No. 23,601. (No model.)

To all whom it may concern:

Be it known that I, GEORGES DELIN, manufacturer, a citizen of Belgium, residing at 7 Boulevard Anspach, Brussels, in the Kingdom 5 of Belgium, have invented certain useful Improvements in Incandescent Gas-Lighting Burners; and I do hereby declare the following to be a full, clear, and exact description of the invention, such as will enable others 10 skilled in the art to which it appertains to make and use the same, reference being had to the accompanying drawings, forming part of this specification.

The object of this invention is to provide a 15 novel incandescent gas-lighting burner provided with a mixing-chamber divided by a wire-gauze and a cylindrical conical-shaped ajutage having three compartments, the heights of which being adjustable, as may be 20 desired, according to the richness and pressure of the gas by varying the distance between the upper and intermediate wire-gauzes, so as to quicken or retard the passage of the gaseous mixture. Said burner is also 25 provided with a closing device surrounding the ejector and by which the gas-jet is prevented from being flickered by the fluctuations of the ambient air and allowing at the same time the admission of the air for combustion.

30 The annexed drawings show two forms of construction of the improved burner.

Figure 1 is a vertical section of one form of the burner. Fig. 2 is a plan view of the same, partly taken on the line T T and partly on the line V V of Fig. 1. Fig. 3 is a vertical section of a second form of the burner. Fig. 35 4 is a plan view of the same, following the line X X of Fig. 3.

The mixing-chamber of the burner is closed 40 at its upper end by a wire-gauze b where the combustion of the gas takes place and is divided into three compartments by the wire-gauze a and the hollow conical-shaped ajutage m. The wire-gauze a and the ajutage m are intended for intimately mixing the combustible gas and air for combustion. In order, however, that the mixing may be perfect, it is necessary that the capacity of the 45 three compartments of said mixing-chamber be capable of regulation according to the richness and the pressure of the gas. To this end the cylindrical-shaped portion of the

ajutage m is split longitudinally by the saw-notches (kerfs) n, so that the sections thus formed on the cylinder may act as a spring 55 and impinge slightly against the inner wall of the tubes c d, and by this means the ring may be securely fixed in place at any convenient height and allow of varying said height as may be desired. The conical-shaped portion of the ajutage is intended for retaining for a moment the air and gas flowing in, as indicated by the arrows in Figs. 1 and 3, in order to obtain an intimate mixing 60 of the same, and the mixture may be pre-heated in passing against the walls of the ajutage.

Figs. 1 and 2 show a regulating device for adjusting the intermediate wire-gauze or perforated metallic sheet a in a relative position 70 to the upper wire-gauze or diaphragm b, which is stationary. As shown in Fig. 1, the tube c of the diaphragm a contains a rack e, operated by a little pinion f, the spindle of which is revolved by means of the wheel h 75 and extends through the notch g of the tube c, which allows the vertical displacement of this latter.

It is to be pointed out that the metallic diaphragms a and b are preferably arranged in 80 such a way that the wires of the diaphragm a intersect with those of the diaphragm b for the purpose of deflecting or twisting the ascending current of the mixture. The same result is obtained if the wire-gauzes are 85 replaced by perforated metallic sheets and are placed in such relative position that the holes therein do not register. The application of the ajutage m and of the metallic diaphragms a and b enables one to obtain an intimate and 90 perfect mixing of the gas and air, which can only be performed by mechanical means—such as chocks, pressing, laminating, and so on—as has been proved by previous practical trials. The ajutage m and the metallic 95 diaphragms are used for the purpose of producing said mechanical effects.

On its lower end the burner is furnished with a casing o, encircling the ejector x. It has a lid or cover o' for preventing the gas-jet from flickering under the influence of the undulations of the ambient air. Both the casing o and its lid o' are provided with apertures p p for the ingress of the air for com-

bustion. The section of the passage for the gas within the ejector, and consequently the quantity of gas introduced to the burner, are regulated at will by means of a screw *s*, which 5 may have a square or triangular-shaped head, so that said screw should not be turned without a special key, and thus all disturbances would be prevented. In the burner shown in Figs. 3 and 4 the diaphragm *a* is stationary, while the diaphragm *b*, and consequently the space between them, are regulated by means of the intercalated rings *l l'*. These 10 rings, which are of convenient breadth, are arranged between the ring *k*, the stirrup *i*, and the tube *d* of the upper wire-gauze *b*. The ring *k* serves also as bearer for the pipe 15 *c* of the wire-gauze *a*. The intercalated rings afford the advantage that the regulation once made for any room or space to be lighted is 20 made for all, so that one is relieved from adjusting it again. Moreover, the burner is not subject to any disturbance as to the position of the metallic wire-gauzes *a* and *b* by 25 any cause whatever coming from cleaning or otherwise. It is also to be pointed out that the intercalated rings *l l'* can be adjusted according to the composition and richness of 30 the gas and provided with marks, which enables the burner to be regulated with the greatest ease.

In the burner shown in Figs. 3 and 4 the inclosing casing *o* is replaced by a simple gallery *o'*, extending beyond the lower edge of the ring *k* and having apertures *p* for the 35 inlet of air. This gallery is adapted to fulfil the same purpose as the casing *o o'*.

Having thus described my invention and ascertained in what manner it is to be per-

formed, what I claim as new, and desire to protect by Letters Patent, is—

1. In an incandescent gas-lighting burner provided with a mixing-chamber, the combination with an upper apertured diaphragm, of a lower apertured diaphragm, a cylindrical conical-shaped ajutage, and means for adjusting the distance between the upper and the lower diaphragm according to the richness and the pressure of the gas, substantially as set forth. 40

2. In an incandescent gas-lighting burner provided with a mixing-chamber, the combination with an upper apertured diaphragm, of a lower apertured diaphragm, a cylindrical conical-shaped ajutage, and means for adjusting the distance between the upper and the lower diaphragm, the apertures in said diaphragms being arranged out of line with each other for the purpose of producing a thorough mixing of the gaseous elements, substantially as set forth. 50

3. In an incandescent gas-lighting burner provided with a mixing-chamber, the combination with two apertured diaphragms, of a rack and pinion for moving one of them toward and away from the other, for the purpose of accelerating or retarding the passage of the gaseous mixture, substantially as set forth. 55

In testimony whereof I have signed this specification in the presence of two subscriv- 60 ing witnesses.

GEORGES DELIN.
